UNITED STATES PATENT OFFICE.

BENJAMIN L. FLETCHER, OF CINCINNATI, OHIO.

WIRE-FENCE MACHINE.

SPECIFICATION forming part of Letters Patent No. 339,159, dated April 6, 1886.

Application filed November 13, 1885. Serial No. 182,752. (No model.)

To all whom it may concern:

Be it known that I, BENJAMIN L. FLETCHER, of the city of Cincinnati, county of Hamilton, and State of Ohio, have invented certain new and useful Improvements in Wire-Fence Machines, of which the following is a specification.

The various features and advantages of my invention will be readily understood from the following description.

In the accompanying drawings, forming part of this specification, Figure 1 represents in perspective a wire-fence machine embodying my improvements. Fig. 2 is a perspective view illustrating my improved straightening device and the means for operating it. Fig. 3 is a central longitudinal section of the machine represented in Fig. 1. Fig. 4 is a side elevation showing a slight modification in the arrangement of the levers and of the stretching board and pins. Fig. 5 is a perspective view of a twisting-head and its springs.

The frame is shaped to support the machine, and is designated in the drawings by the letter A. The spools B are mounted at one end of the frame and the wires are brought forward, each pair passing through a twisting-head, C. A pair of springs, C', are attached to each twisting-head, and through an eye in the end 30 of each spring C' one of the wires passes. Each twisting-head is provided with a toothed wheel, D.

The preferable means of operating the twisting-heads is by means of an endless chain, d, which passes alternately over and under the toothed wheels D, engaging with their teeth, and after passing over the last wheel returns under the wheel to the operating-wheel D' at the side of the machine. The operating-wheel 40 D' is worked by the crank E.

A suitable device is to be employed for forcing the paling into place between the wires and holding the paling there preparatory to the latter being secured in position by the 45 twist of the wires. One description of device for this purpose is briefly illustrated, and consists as follows: F is a handle which operates the fingers G in forcing the paling into place between the wires. The table H is mounted on side pieces, h, which raise it above the level of the frame A. The side pieces, h,

are provided with the slots h', which allow the table to be adjusted with reference to the twisting-heads. On the under surface of the table H two brackets, I, are rigidly fastened. Each 55 bracket I has a rod, k, pivoted in it, and the other ends of the rods k are united by a cross-piece, k'. The three pieces k k' constitute the yoke K, which may instead be made in one piece. The leaf L extends down from the 60 table H, and has the leaf L' hinged to it. The leaf L' passes under the rod k', and has the rod loosely attached to its upper surface by the strap l. The lever M is fulcrumed to the support N, which projects downward from the 65 table H. One end of the lever M is attached to the leaf L' and the other end is pivoted to the connecting-rod O. The other end of the rod O is pivoted to the handle P, which in its turn is fulcrumed to the support Q. Pins R, 70 preferably two in number, are loosely pivoted to the rod k' and extend upwardly, passing through openings h² in the table H. At the end of the machine a drum is placed, on which the fence is wound as fast as it is made. This 75 drum is provided with a ratchet-wheel, T, which is held by the pawl t, pivotally attached to the frame A. An arm, U, swings loosely on the axle of the drum and extends beyond the edge of the ratchet T. It is connected to the lever 80 S by the short connecting-rod u. This connecting-rod u is provided with a dog, u', which engages with the teeth of the ratchet T. The foot-lever S is fulcrumed to the side of the frame, and its short end is held down by the 85 spring S'.

In describing the operation of the machine, let us suppose that the fence has been started, as shown in Fig. 1: A paling is put by hand in place between the wires and is then driven 90 home against the twists by fingers G, operated by handle F. The crank E is now turned and the wires are twisted, holding the paling firmly in position. The foot-lever S is now worked up and down several times, winding the fence 95 on the drum. As the last paling secured approaches the edge of the table H it is met by the pins R, which project slightly above the surface of the table. As a rule the paling will reach one pin before touching the other, thus 100 showing that the fence is beginning to weave crooked. The fence is now tightened by means

of the foot-lever S until the paling rests against both pins. This makes the fence straight, and all is ready for the introduction of the next paling. When the next paling has been secured in position and the wire twisted, the handle P is depressed, lowering with it the pins R, so that when the foot-lever S is operated the fence may be wound on the drum, drawing the paling over the ends of the depressed pins R. As soon as the paling has passed the pins the handle P is released, forcing the pins R to pass up through the table, and project above the latter in time to straighten the paling last inserted.

To insure the return of the pins R to position, it is sometimes necessary to apply a weight or spring to the connecting-rod O, or other suitable part. By means of this device the fence is kept perfectly straight.

I will now describe another feature of my invention. The twisting-heads consist of the cylindrical frame C and the spring-pieces C'. The latter each consist of a straight portion, X, and a flange or bent portion, y, located at the free end portion of the spring-piece, and containing an opening, h. The wire passes through one of the openings d², and thence through openings h³ of flange y on the same side of the twisting-head, as opening or eye d². Each of the flanges y is provided with an extension, Z, which latter extends outward toward the fence-reel end of the machine. These extensions Z are valuable ad-

ditions to the twisting-head. They prevent the wires while being twisted from slipping off the ends of the flanges y y. They enable the wires to be twisted closer. They enable the twisting to be started closer to the picket, and enable the operator to have more perfect control of the wires. The interposition of these extensions between the wires enables an advantageous leverage to be obtained upon them while being twisted.

While the various features of my invention are preferably employed together, one or more of said features may be used without the remainder, and in so far as applicable one or more of said features may be employed in connection with devices for making wire fence, other than those specifically herein set forth.

What I claim as new and of my invention, and desire to secure by Letters Patent, is—

1. The combination of the table H, pins R, yoke K, levers L, M, and P, and connecting-rod O, substantially as and for the purposes specified.

2. The twisting-head having spring-pieces C', each consisting of a piece, X, flange y, and having opening h, and extension piece or lip Z, substantially as and for the purposes set forth.

BENJAMIN L. FLETCHER.
